UNITED STATES PATENT OFFICE.

EPHRAIM B. BISHOP, OF SAN FRANCISCO, CALIFORNIA, ASSIGNOR OF ONE-HALF TO ELIJAH H. GADSBY, OF SAME PLACE, AND CHARLES R. ALLEN, OF OAKLAND, CALIFORNIA.

TRACK-CLEARER.

SPECIFICATION forming part of Letters Patent No. 297,910, dated April 29, 1884.

Application filed November 23, 1883. (No model.)

To all whom it may concern:

Be it known that I, EPHRAIM B. BISHOP, a citizen of the United States, residing at San Francisco, in the county of San Francisco and 5 State of California, have invented certain new and useful Improvements in Track-Clearers, of which the following is a specification.

My invention relates to an improved track-clearer adapted to be attached to the forward 10 end of the railroad-cars, the object being to provide a means whereby obstructions may be easily and quickly pushed or rolled from between the rails of a railway-track and the liability to accident avoided. This object I accomplish by the means illustrated in the accompanying drawings, in which—

Figure 1 is a plan view of my improved track-clearer. Fig. 2 is a front elevation of the same. Fig. 3 is a section through the rubber-faced 20 wheel.

Similar letters of reference are used to indicate like parts throughout the several views.

My track-clearer consists, essentially, of two 25 conical rollers suspended from the floor of the car and extending forward and outward toward the center of the track, and arranged to rotate in a forward and upward direction, said conical rollers being actuated by the frictional contact with the car-wheels of rubber-faced disks 30 that are mounted on the rear ends of the spindles that carry the rollers. These rollers A A' are made conical or tapering from rear to front, and may be made of any suitable material, either solid or hollow, and are provided 35 with spindles B B, by which they are hung in suitable bearing-blocks. Upon the rear end of the spindles I key the plate wheel or disk C, having a rubber face, C', as shown in Fig. 3. The forward spindles, or those situated at the 40 apex of the cone-shaped rollers, are journaled in the bearing-block D, which is suspended from the floor of the car by a rod, D', and allowed to hang directly over the center of the track. Braces or stay-rods D' D' are also provided, by which the said bearing-block is braced and 45 steadied in its position. One of these forward spindles is carried through its bearing-block, and its projected end is provided with

a brush-wheel, E, as shown in Fig. 1. The rear spindles, or those situated at the base of the conical rollers, are journaled in the bearing blocks or plates F F, which are suspended from the floor of the car by the rods F', as is clearly shown in Fig. 2. All of these suspending-rods are provided with turn-buckles, as shown, or some other well-known device, whereby the position of the conical rollers with reference to the track-rails may be regulated. The rubber-faced wheels C are to be so hung that they will be in constant contact with the outer forward edge of the tread of the wheel, in order that the revolution of the car-wheels may be imparted to the aforesaid rubber-faced wheels and the conical rollers. The rollers A A' are to be hung so that the lower edge thereof will approach closely to the level of the track and be in the same horizontal plane, and the axes of the rollers should be at right angles to each other and extend across the trackway at an angle of about forty-five degrees. The surface of each cone or roller is traversed by a series of spirally-arranged brushes, ribs, or bands of rubber, G G, as shown in Fig. 1, the object of these spirals or raised rubber screw-threads being to feed or work any obstruction that may be encountered away from 55 toward the center of the trackway.

It should here be remarked that, if necessary, the rollers may be attached to a supplemental frame, which can be lowered by the action of a lever-handle placed within reach of an attendant, for the purpose of allowing the conical rollers to drop upon the track and act as a check to stop the rotation of the car-wheels and the forward motion of the car.

When in operation the rotation of the car-wheels will produce a constant rotation of the track-clearers or conical rollers, which revolve forward and upward, and thereby push forward and outward any obstruction which may 90 be upon the track, and prevent it from being drawn beneath the car or car-wheels.

I am aware that a track-clearer has heretofore comprised a hinged frame supporting a transverse shaft carrying friction-wheels which 95 bear against the pilot-wheels of the locomotive,

and also spur-wheels which rotate outward and upward when the locomotive moves forward. This, however, I do not claim.

Having thus described my invention, what I claim, and desire to secure by Letters Patent, is—

1. A track-clearer for railway-cars, consisting of two conical rollers hung from the car-floor in suitable journal-boxes, and operated by the frictional contact of the car-wheels with rubber-faced wheels upon the spindles of the rollers, substantially as shown and described.

2. In a track-clearer for railroad-cars, the conical rollers A A', suitably journaled beneath the body of the car, and having spindles

B B, and rubber-faced friction-wheels C C, constructed, arranged, and operating substantially as shown and for the purpose set forth.

3. In a track-clearer for railroad-cars, the conical rollers A A', provided with spirally-arranged brushes or raised rubber bands G G, and brush-wheel E, substantially as shown, for the purpose set forth.

In testimony that I claim the foregoing I have hereunto set my hand and seal.

EPHRAIM B. BISHOP. [L. S.]
